Primary Examiner—Brian N Vinson*(74) Attorney, Agent, or Firm*—Brinks Hofer Gilson & Lione(57) **CLAIM**

We claim the ornamental design for an optical disc drive for medical use, as shown and described.

DESCRIPTION

FIG. 1 is a top perspective view of an optical disc drive for medical use of the present invention;

FIG. 2 is a front view thereof;

FIG. 3 is a rear view thereof;

FIG. 4 is a first side view thereof;

FIG. 5 is a second side view thereof;

FIG. 6 is a top view thereof; and,

FIG. 7 is a bottom view thereof.
